BY THEIR ATTORNEYS

Williamson & Neuchter

UNITED STATES PATENT OFFICE.

GEORGE W. RAY AND WILLIAM V. HARRINGTON, OF MINNEAPOLIS, MINNESOTA; SAID RAY ASSIGNOR TO SAID HARRINGTON.

LAMP-DIMMER.

1,335,918.

Specification of Letters Patent. Patented Apr. 6, 1920.

Application filed May 8, 1919. Serial No. 295,676.

To all whom it may concern:

Be it known that we, GEORGE W. RAY and WILLIAM V. HARRINGTON, citizens of the United States, residing at Minneapolis, 5 in the county of Hennepin and State of Minnesota, have invented certain new and useful Improvements in Lamp-Dimmers; and we do hereby declare the following to be a full, clear, and exact description of the invention, such as will enable others skilled 10 in the art to which it appertains to make and use the same.

Our invention relates to dimmers for vehicle headlights and the like; and has for its 15 object to combine the dimmers with the lenses and arrange the same so as to deflect the upwardly projecting rays of light from the lamps, to prevent glare, and direct said rays onto the road, which, together with 20 the rays of light passing under the dimmers, throws a light, substantially the full strength of the lamps, upon the road where the same is needed.

To the above end the invention consists of 25 the novel devices and combinations of devices hereinafter described and defined in the claims.

In the accompanying drawings, which 30 illustrate the invention, like characters indicate like parts throughout the several views.

Referring to the drawings:

Figure 1 is a front elevation of an automobile headlight having one of the combined lenses and dimmers incorporated 35 therein;

Fig. 2 is a view principally in vertical section taken on the line 2—2 of Fig. 1;

Fig. 3 is a rear elevation of the combined lens and dimmer removed from the head- 40 light;

Fig. 4 is a vertical section taken on the line 4—4 of Fig. 3; and

Fig. 5 is a view corresponding to Fig. 4, but showing modified means for securing the 45 dimmer to the lens.

Of the parts of the automobile headlight illustrated it is important to note the casing 6, reflector 7, lamp bulb 8 and lens 9. The dimmer comprises a plurality of thin trans- 50 lucent horizontal slats 10, having non-lus- trous surfaces and are preferably made from a non-metallic light-absorbing material, such as a soft white wood left in its natural state without polish or finish.

55 The slats 10 are secured to the back of

the lens 9 in oblique positions and vertically spaced equal distances apart, with the lower longitudinal edge of one slat in substantially the same horizontal plane with the upper longitudinal edge of the adjacent slat. The 60 lower longitudinal edges of the slats 10 engage or substantially engage the back of the lens 9 and incline rearward therefrom, preferably at angles of substantially 28 degrees to the plane of the lens. 65

As one means for securing the slats 10 to the lens 9 there is cast or otherwise formed on the back of said lens, as shown in Figs. 1 to 4, inclusive, two diametrically opposite segmental ribs 11 having oblique slots or 70 seats 12 in which the ends of said slats are mounted. The lower ends of the ribs 11 terminate in a horizontal plane slightly below the axle of the lens 9 and the upper ends thereof almost meet at the top of the 75 lens. These ribs 11 are located sufficiently inward of the edge of the lens 9 to clear the reflector 7 and are concentric therewith. By referring to Fig. 2, it will be noted that the slats 10 extend from the top of the reflector 80 to a point substantially equal to the width of one of the slats below the projected horizontal axis of the lamp bulb 8.

In the construction shown in Fig. 5, the slats 10 are secured to the lens 9 by casting, 85 or otherwise forming on the back thereof, circumferentially spaced lugs 13 having open oblique seats 14 to receive the ends of said slats.

As previously stated, the dimmer will deflect the greater portion of the upwardly projecting rays of light from the headlight onto the road and a portion of said light will be absorbed by the slats of the dimmer and diffused thereby. Owing to the nature 95 of the dimmer slats, no glare will be imparted thereby and the light passing therethrough will be of a very soft character.

By forming the slat holding means with the lens, said slats are securely held against 100 vibration with respect to the lens, and, as said slats are supported only at their ends from the lens, no vertical obstructions to the lens are necessary to connect said slats. The combined lens and dimmer is very neat 105 and compact in appearance and said dimmer remains in the same relation to the lens, at all times, thus making the application of the lens and dimmer to the casing extremely simple. 110

What we claim is:—

1. A combined lens and dimmer for headlights and the like, comprising a plurality of slats that are oblique to the plane of the lens, and seats integrally formed with the lens for holding the slats.
2. A combined lens and dimmer for headlights and the like, comprising a plurality of translucent slats that are oblique to the
- 10 plane of the lens, and seats integrally formed with the lens for holding the slats.
3. A combined lens and dimmer for head-

lights and the like, comprising a plurality of translucent slats that are oblique to the plane of the lens, and ribs integrally formed 15 with the lens and having seats in which the ends of the slats are mounted.

In testimony whereof we affix our signatures in presence of two witnesses.

GEORGE W. RAY.

WILLIAM V. HARRINGTON.
